UNITED STATES PATENT OFFICE.

GEORGE F. ZAUN, OF SAN BERNARDINO, CALIFORNIA.

ROLLING-STOCK.

1,312,465.

Specification of Letters Patent.

Patented Aug. 5, 1919.

Application filed July 22, 1918. Serial No. 246,107.

To all whom it may concern:

Be it known that I, GEORGE F. ZAUN, a citizen of the United States, residing at San Bernardino, in the county of San Bernardino and State of California, have invented new and useful Improvements in Rolling-Stock, of which the following is a specification.

This invention relates to rolling stock, and more particularly to railway cars for handling coal, road-repairing and road-building material, such as gravel, sand and earth, and other materials and substances which may readily be discharged from such cars by gravity, as through drop-bottoms, without the necessity of unloading the same manually or in any other positive manner. While drop-bottom cars have hitherto been constructed, no such car has been provided and organized in such manner as to permit of a diversity of distributions or flows or discharges of the material, so that it might be directed either downwardly, laterally, or both laterally and downwardly, or convergingly downwardly, that is, in streams proceeding from opposite sides of the car, or divergently downwardly in streams proceeding from opposite sides of the car. Ordinarily such drop-bottom cars merely provide for and permit the mere dumping or dropping of the load in a discharging action substantially vertical, and not subject to the possibility of producing diversified direction of flow or discharge to distribute or dispose or direct or deflect the load or portions thereof in a predetermined manner and for definite objects and purposes. In accordance with the present invention, and the diversified directions and manners in which the load and its portions may be discharged or directed, many useful and beneficial objects may be attained, substantially automatically, and which objects have heretofore been capable of accomplishment only by costly and time-consuming manual and other operations. For instance, in accordance with the present invention, I provide a drop-bottom car from which loads of coal, cement, earth, gravel, sand or other broken or comminuted or finely divided materials may be discharged in two streams, in opposite lateral directions, as into separate bins or receptacles or piles or upon the sides of the right of way for building embankments or fills. Or, the load may be discharged all toward one side or the other, or it may be discharged

all substantially along the longitudinal median line of the car, as for instance, in depositing or distributing ballast upon a roadbed. All of this is accomplished by a certain provision and combination and inter-relation and association of parts and features, subject and responsive to control to produce predetermined results, and in fact, subject to absolute control without disturbance of any working condition set up and desired to be maintained. In other words, the parts and features when set up and arranged and adjusted for one particular dumping action or unloading or distributing action, are locked against any disturbance of such condition or adjustment until voluntarily released to restore the parts and features to their normal positions or conditions or to throw them into other positions or bring them into other conditions.

The invention has for its object the provision of improved rolling stock of the general character stated which will be superior in point of relative simplicity and inexpensiveness of construction and organization, taken in conjunction with positiveness and efficiency and reliability in service, definiteness and convenience in control, durability, freedom from liability to get out of repair, and adaptability to a wide range of conditions of use and service, and which will be generally superior in efficiency and serviceability.

With the above and other objects in view, the invention consists in the novel and useful provision, formation, construction, combination, organization, inter-relation and association of parts, members and features, all as hereinafter described, shown in the drawings, and finally pointed out in claims.

In the drawings:

Figure 1 is a bottom plan view, broken away for convenience in illustration, at one end of a railway car constructed and organized in accordance with the invention;

Fig. 2 is a side elevation of the same;

Fig. 3 is an end elevation of the same;

Fig. 4 is a partially transverse sectional view, taken upon the line $\alpha^{4-5}-\alpha^{4-5}$, Fig. 2, 105 and looking in the direction of the accompanying arrows;

Fig. 5 is similarly a partially transverse detail sectional view taken upon the same plane of section, and showing the parts of Fig. 4 in condition subsequent to adjustment;

Fig. 6 is a detail vertical sectional view taken upon the line x^6-x^8 , Fig. 1, and looking in the direction of the appended arrows;

Fig. 7 is a transverse sectional view taken upon the line x^7-x^7 , Fig. 2, and looking in the direction of the appended arrows;

Figs. 8 to 12 inclusive, are detail transverse sectional views taken upon the line x^7-x^7 , Fig. 2, and looking in the direction 10 of the appended arrows; and,

Fig. 13 is a detail transverse sectional view taken upon the line $x^{13}-x^{13}$, Fig. 1, and looking in the direction of the accompanying arrows.

15 Figs. 8 to 13 inclusive, are upon enlarged scales.

Corresponding parts in all the figures are designated by the same reference characters.

Referring with particularity to the drawings, the improved railway car shown there-in comprises longitudinal side sills or frame members 14 and a central longitudinal frame member or beam 15, together with the usual upright side walls 16, end walls 17, and 25 end sills 18. In these respects the general frame construction of the car may be in accordance with preference, all within the limits of suitable durability and proper railway practice. At each side of the longitudinal beam 15 is a series or plurality of drop-sections a , which are adapted to be deflected, each, laterally in either direction, as clearly disclosed in Figs. 8 to 12 inclusive, with the exception of certain drop-sections 30 b at each end of the car, two at each side at each end, which are adapted each to drop or tilt only in one direction, and that toward the side of the car at which such drop section is disposed. At each side of the 35 car, longitudinally, is provided a pair of rock shafts, c and d respectively, and which are journaled in connection with the frame members of the car, and are provided with dogs e which co-engage with hooked edge portions 19 upon the section a , to maintain the respective edge portions in normal positions, that is, in positions coincident with the plane in which such drop-sections lie 40 when horizontally disposed. These dogs and hooked edge portions of the drop-sections co-operate with supporting members f , a plurality of which are disposed at each 45 side of the longitudinal center of the car, in a series extending longitudinally of the car, and mounted upon a rock shaft 20. These 50 rock shafts are journaled in hangers 21 which extend transversely of the car between the central longitudinal beam 15 and the side frame members 14. These supporting members f are preferably cam or sector-shaped, their arcuate crowns being provided with 55 rollers or anti-friction devices 22 adapted to engage the drop-sections a and b , and to limit the drop action of each of the same 60 in either direction permitted by suitable 65

adjustment of the dogs e , and also adapted to furnish the main support for the respective drop-section when the same is in horizontal or normal position, and thus in the main support that portion of the load of 70 the car disposed upon such drop-section, all as shown in Figs. 8 to 13 inclusive. The rock shaft 20 and rock shafts c and d are all interrupted centrally of the car, that is, centrally between the ends of the car, so 75 that the car is subdivided into two working units, each of which includes half of the drop-sections a , one pair of drop-sections b , half of the supporting means or cam members f , and half of the dogs e . At each end 80 of each half of the rock shaft 20, and at each end of the car, is provided a pinion 23 fixed to such shaft, and which meshes with a gear 24 fixed upon a short stub shaft 25, mounted in the respective end sill 18. For 85 each gear 24 is an operating arm 26 whereby the respective rock shaft may be operated to throw the supporting members or cam members f upon it into any one of the positions indicated in Figs. 8 to 13 inclusive. 90 B designates locking means disposed at each end of the car and at each side of each end of the car for the two rock shafts c and d and the rock shaft 20, the ends of which terminate at each side of each end of the 95 car. These locking means comprise in the first place, locking plates 27 upon the shafts d and 28 upon the shafts c , and locking plates 29 upon the shafts 20. With these locking plates co-operate locking fingers 27^a 100 for the plates 27, 28^a for the plates 28, and 29^a for the plates 29. Each finger 27^a together with a finger 29^a is mounted upon a locking arm 30 which is pivotally connected as at 31 with the respective rock 105 shaft c .

Each of the locking fingers 28^a with one of the locking fingers 29^a, is mounted upon a locking arm 32 which is pivotally connected as at 33 with the respective rock 110 shaft d . The rock shafts c have crank arms 34 at their ends, at the ends of the car, and by these such rock shafts may be turned. The rock shafts d have pivoted operating arms or cranks 35 at their ends, at the 115 ends of the car, and by these the rock shafts d may be turned, such pivoted arms 35 being adapted to be swung over stops 36 at the ends of the car, to prevent turning of the shafts d until such pivoted arms are 120 released from such stops. The locking arms 30 and 32 are guided at their locking fingers or terminal portions 27^a and 28^a in suitable openings in the frame members 14 of the car, as indicated in Fig. 2, and in 125 Fig. 4 in section. Any suitable arrangement and mounting of these locking arms may be adopted, as will be obvious.

The operation, method of use and advantages of the improvements in rolling 130

stock or railway cars will be readily understood from the foregoing description, taken in connection with the accompanying drawings, and the following statement:

- 5 Normally the drop-sections *a* and *b* are in horizontal positions, as shown in Fig. 7 or Fig. 1, or as indicated in Fig. 8 as to the sections *a*. The sections *b* are operated in the same manner as the sections *a*, in tilting or dropping them downwardly and laterally toward the sides of the car, as shown in Fig. 13, but their inner hooked edge portions 19 are permanently engaged with fixed dogs *k* upon the central frame member 15 10 of the car. The drop-sections in normal positions are in the main supported with their loads by the supporting or cam members *f*, and are incidentally supported by the dogs *e* or fixed dogs *k* with the movable dogs *e*, in consideration of the drop-sections *b*. If it be desired to tilt the drop-sections downwardly and outwardly at each side of the car, as shown in Fig. 11, toward the same side of the car, as shown in Fig. 9, 15 or in Fig. 10, or toward the center of the car as shown in Fig. 12, or as to the section *b* downwardly and oppositely, as shown in Fig. 13, the rock shafts *c* and *d* are manipulated to release the drop-sections *a* or *b* accordingly, by freeing the hooked edge portions 19 of the drop-sections from the respective dogs, and thus permitting the resultant slant or inclination of the drop-sections to occur. Such, however, only occurs 20 after the rock shafts 20 are suitably turned, both being turned if inclination of both lateral series of drop-sections is required, and only one being turned if only one lateral series of drop-sections is desired to be tilted. 25 This is done either by manipulating the fixed cranks 34 or the pivoted cranks 35. It is impossible to manipulate both the rock shaft *c* and *d* at either side of the car, but the rock shaft *c* at one side may be rocked with the rock shaft *d* at the other side. Thus it is impossible to release the sections *a* at both side edges so as to entirely drop the same or free them so that they may be displaced entirely. This is due to the operation 30 of the locking means *B*, whereby, as will be readily perceived, if the rock shaft *c* at one side of the car is turned, the locking fingers 27^a coöperating with the plate 27 prevents the rock shaft *d* from being turned; and reciprocally if the rock shaft *d* be turned the locking finger 28^a coöperates with the locking plate 28 to prevent the rock shaft *c* from being turned. Likewise, whenever either rock shaft is turned the 35 respective rock shaft 20 at the same side of the car is locked against turning in one direction by the respective locking finger 29^a coöperating with the locking plate 29. This permits such rock shaft 20 to be turned 40 through the pinion 23 and gear 24 by the

operating arm 26 only in that direction which will permit the supporting and cam member *f* to take an inclination proper to permit the inclination of the respective drop-sections *a* which are assumed consequent upon the rocking of the respective rock shaft *c* or *d*. In other words, after either such rock shaft at one side of the car is turned, the rock shaft 20 at the same side of the car and associated with that group of drop-sections, may be turned to incline the members *f* connected with it so as to permit the respective drop-sections to take the inclinations for which they have been released, all as clearly indicated in Figs. 8 to 13 inclusive. When the rock shaft 20 has been thus turned the respective drop sections *a* come to rest upon such members which serve as supports for the same when in inclination, in conjunction with the hooked edge portions 19 and the co-engaging dogs *e* or *k* which are still in coöperation. The object of permanently supporting the bottom-sections *b* at their inside lateral edges is to prevent tilting of these sections *b* toward the center of the car, which would result in a load thereof being discharged onto the trucks and wheels of the car.

It is manifest that by the use of this invention the load in the car, at each end of the same, may be discharged entirely toward either side of the car, half toward each side of the car or entirely toward the center of the car,—all as the requirements of unloading, road-way building, ballasting, filling, embanking or other operation may require.

It is manifest that the invention provides for a car organization which is of extreme versatility and adaptability to varying demands of unloading or road building or repairing or the like, and adaptability to many various and widely varying uses, and that many changes and departures from the construction herein disclosed and pictured in the drawings, may be made, in adapting the invention to varying conditions of use and service, without departing from the spirit of the invention.

Having thus disclosed my invention, I claim and desire to secure by Letters Patent:

1. A car provided with a bottom section adapted to be inclined in a plurality of directions, means for releasably supporting said bottom section at a plurality of points, and an adjustable member adapted to support said bottom member and adapted to be inclined to accommodate said bottom member in a plurality of different inclinations.

2. A car provided with a bottom section adapted to be inclined in a plurality of directions, means for releasably supporting said bottom section at a plurality of points, and an adjustable member adapted to support said bottom member and adapted to

be inclined to accommodate said bottom member in a plurality of different inclinations; means being provided for releasing said bottom member at either of said 5 points of support, and locking means for preventing such release at more than one point at any one time.

3. A car provided with a bottom section adapted to be inclined in a plurality of directions, means for releasably supporting said bottom section at a plurality of points, and an adjustable member adapted to support said bottom member and adapted to be inclined to accommodate said bottom 15 member in a plurality of different inclinations; means being provided for releasing said bottom member at either of said points of support, and locking means for preventing such release at more than one point 20 at any one time; said locking means likewise preventing adjustment of said supporting member other than to adapt it for support of said bottom member in the inclination predetermined by the operation of said 25 means for releasing said bottom member.

4. A car provided with a longitudinally arranged rock shaft, a dog upon said rock shaft, a tiltable bottom member coöperating with said dog, and means for turning 30 said rock shaft; a supporting member likewise being provided for said bottom member and adapted for adjustment to accommodate such tilting action of the latter; means being provided for locking said rock shaft 35 against turning and likewise for locking said supporting member against adjustment in a certain direction.

5. A car provided with a longitudinally arranged rock shaft, a dog upon said rock 40 shaft, a tiltable bottom member coöperating with said dog, and means for turning said rock shaft; a supporting member likewise being provided for said bottom member and adapted for adjustment to accommodate such tilting action of the latter; means being provided for locking said rock shaft 45 against turning and likewise for locking said supporting member against adjustment in a certain direction; said supporting member being provided with a rock shaft upon which such supporting member is mounted, and means being provided for turning said latter rock shaft.

6. A car provided with longitudinally 55 extending rock shafts, dogs upon said rock shafts, bottom members releasably engaged with said dogs, and separate means for turning said rock shafts to release said bottom members from either of the same;

inter-related locking means being provided 60 for preventing turning of each of said rock shafts when the other thereof is turned.

7. A car provided with longitudinally extending rock shafts, dogs upon said rock shafts, bottom members releasably engaged 65 with said dogs, and separate means for turning said rock shafts to release said bottom members from either of the same; locking means being provided for preventing turning of each of said rock shafts 70 when the other thereof is turned; and a further rock shaft provided with supporting members for said bottom members, said locking means being adapted to prevent turning of said last named rock shaft in 75 more than one direction when one of said first named rock shafts is turned.

8. A car provided with three longitudinally extending rock shafts, a bottom section releasably engaged with two of said 80 rock shafts at opposite edges thereof, and a swinging cam member projecting laterally from the third rock shaft which is arranged under the said bottom section, said swinging cam member being adapted to be swung 85 into engagement with the bottom section to support same.

9. A car provided with three rock shafts ranging longitudinally of the car, a bottom section releasably engaged with two of 90 said rock shafts at opposed points, and a supporting member for said bottom member mounted upon a third rock shaft; means being provided for locking one of 95 said two rock shafts when the other is turned, and for locking the third rock shaft as against turning in more than one direction.

10. A car provided with three rock shafts ranging longitudinally of the car, 100 a bottom section releasably engaged with two of said rock shafts at opposed points, and a supporting member for said bottom member mounted upon a third rock shaft; means being provided for locking one of 105 said two rock shafts when the other is turned, and for locking the third rock shaft as against turning in more than one direction; separate means being provided for turning each of said rock shafts. 110

In testimony whereof, I have signed my name to this specification in the presence of two subscribing witnesses.
